UNITED STATES PATENT OFFICE.

D'ORSAY McCALL WHITE, OF DETROIT, MICHIGAN, ASSIGNOR TO CADILLAC MOTOR CAR COMPANY, OF DETROIT, MICHIGAN, A CORPORATION OF MICHIGAN.

HYDROCARBON-MOTOR.

1,316,527.

Specification of Letters Patent. Patented Sept. 16, 1919.

Application filed November 11, 1915. Serial No. 60,813.

To all whom it may concern:

Be it known that I, D'ORSAY McCALL WHITE, a loyal subject of the King of England, and resident of Detroit, Wayne county, 5 State of Michigan, have invented certain new and useful Improvements in Hydrocarbon-Motors, of which the following is a specification.

This invention relates to hydrocarbon motors, and particularly to hydrocarbon motors of the so called V type.

One of the objects of this invention is a novel arrangement and construction of the valve operating mechanism of a V type 15 motor.

Another object is to provide a valve operating mechanism, which is simple in construction and efficient in operation; which may be easily assembled and disassembled 20 and is comparatively inexpensive to manufacture.

Another object of this invention is to provide a motor of the V type, having its valves and operating mechanism so arranged that 25 the valve mechanism of opposite cylinders may be operated by the same cam, or cams, through suitable intermediate members or rocker arms, which may be assembled in position and disassembled therefrom, without disturbing correlated parts, such as the cam shaft and the valve mechanism proper; and to provide a valve mechanism having these parts so arranged that the lift on the tappets will be straight upward, instead of 30 having a lateral thrust component, as in previous valve operating mechanisms of this type.

Other objects will appear from the following description, taken in connection with 46 the drawings, which form a part of this specification, and in which:

Figure 1 is a longitudinal vertical section, substantially on the line 1—1 of Fig. 2 of a motor embodying a form of this invention, showing parts broken away;

Fig. 2 is a transverse view, showing parts broken away;

Fig. 3 shows a side view of an assembly of a preferred form of valve operating 50 rocker arms and supporting members;

Fig. 4 shows a face view looking upwardly, of the assembly shown in Fig. 3; and

Fig. 5 is an enlarged fragmentary view of the valve operating mechanism.

Referring to the drawings, 10 represents the motor base or crank case, on which is suitably mounted in V relation a plurality of cylinder blocks 11 and 12, which are secured thereto, as by bolts 13. The cylinders 60 are provided with pistons 14, which are adapted to be connected with the crank shaft 15 by means of connecting rods 16 and 17, suitably attached at their upper ends to the pistons 14, by means of the usual piston 65 pins 18.

The crank shaft 15 may be mounted in suitable bearings 19 in the crank case 10, which are secured therein by means of detachable caps 20 and bolts 21. It will be 70 noted that as the cylinders in the blocks 11 and 12 are arranged opposite each other, one of each of the connecting rods 16 and 17 are adapted to be journaled on a single crank 22. This may be done by providing one of 75 the connecting rods, such as 16, with a forked portion 16', which has suitably secured thereto, as by pins 18, a journal member 19, which may be secured in position in the detachable caps 23, as by bolts 24. The 80 other connecting rod 17 is adapted to be sleeved within the yoke arms on the journal member 19 and secured in position, as by cap 25 and bolts 26. Arranged adjacent one end of the crank shaft 15 is a driving gear 85 27, which may be secured thereto, as by a bolt 28, and a fly wheel 29 may be secured to the opposite end of the crank shaft by bolts 30.

Each of the cylinders is provided with 90 an inlet valve and an exhaust valve mechanism, arranged in the adjacent or inner sides of the cylinders and comprising a bushing 31, suitably arranged in the upper portion of the cylinder and having mounted 95 therein a valve 32 of the puppet type, which is provided with a collar 33, arranged on the stem 34 thereof. A valve closing spring 35 is suitably arranged between the cylinder and the collar 33. Adjustable tappets 36 100

are arranged in bushings 37, which may be held in position in the crank case 10, as by a pressed fit, and arranged on the upper end of the tappets is an adjustable contact portion 36' which may be locked in position by nuts 38 arranged on the different parts of the tappets for adjusting a proper clearance between the valve stem 34 and tappets 36. The actuating means for the 10 valves will now be more particularly described.

A single cam shaft 39, which is adapted to operate the valves in opposite cylinders, is provided with a plurality of cams 40 and 15 bearings 41 and it may be arranged in bosses formed integral with the crank case 10 above the crank shaft 15 and in the same vertical plane therewith, by an endwise movement thereof. This cam shaft may be 20 secured in position by means such as a pin 42, and may be provided with a means for driving it, such as a gear 43, which is arranged adjacent its front end and adapted to be secured thereto, as by a bolt 44. A 25 driving connection from the gear 27 to the gear 43, in the form of a chain 45 is provided. A cover plate 46 for the driving mechanism, arranged at the front end of the motor, may be secured to the crank case 30 10, as by bolts 47.

It will be understood that the crank case is provided at its upper side with an opening 48, which is adapted to be closed by a cover or supporting plate 49, which may 35 be secured in position as by bolts 50. The supporting plate 49 is provided with a plurality of sets of downwardly extending lugs 51 and 51', in which are arranged suitable bushings 52 for supporting rods 53 and 53', respectively. It will be understood that in an eight cylinder motor, as illustrated, having its cylinders arranged at a ninety degree angle, each of the cams is adapted to 40 operate two valves arranged in opposite cylinders, as shown. This may be done by arranging the pairs of rocker arms 54 and 55 on the respective rods 53 and 53' on opposite sides of the cam shaft 39 and each pair adapted to be actuated by a single 45 cam 40 and to operate a valve in opposite cylinder blocks alternately. These rocker arms 54 and 55 are held in proper relation by means of the spacers 56, which may be secured to the rods 53 and 53' by pins 57. 50 It will be noted that the rocker arms are provided with rollers 58 and renewable contact points 59 and that while the axes of the cam shaft and tappets do not coincide, the relation of the cams, rocker arms and 55 tappets is such that the lift will produce a minimum side thrust component. It will also be understood that either the valve tappets or the contact points 59 may be curved on a radius to give a point or line contact 60 between these members.

It will be seen from the above description that the cam shaft and the parts arranged thereon, may be assembled and disassembled in position without removing the valve actuating rocker arms, provided they 70 are lifted up, so that they will not interfere with the cams on the withdrawal of the shaft, and that the cover plate 49 is adapted to have the rocker arms arranged thereon in operative relation, as a unit, while on 75 the bench and may then be arranged on the crank case without disturbing the cam shaft or its securing means.

It will also be understood that the supporting plate and its rocker arms may be 80 removed as a unit from the crank case without disturbing the mounting of the valve mechanism, its tappets or the cam shaft, or disturbing the various necessarily delicate adjustment of these parts. 85

While I have described and illustrated one of my preferred forms of invention, it will, of course, be understood that various modifications may be made, by one skilled in the art, without departing from the 90 spirit or scope of my invention, and which will be covered herein.

Having thus described my invention, what I claim and desire to secure by Letters Patent is:—

1. In an internal combustion engine, the combination with a crank case, a cam shaft, bearings therefor mounted in said crank case, and means for securing said cam shaft in position in said bearings, of a supporting 100 plate, rocker arms mounted on said supporting plate and adapted to be operated by said cam shaft, and means for detachably securing said supporting plate to said crank case, the relation of said supporting plate, the 105 rocker arms mounted thereon, the cam shaft and its bearings, being such that the supporting plate may be removed from said crank case without disturbing the mounting of either said rocker arms or said cam shaft on 110 the plate and the crank case respectively.

2. In an internal combustion engine, the combination with a crank case, of a plurality of cylinders mounted thereon in V relation and provided with reciprocating valve mechanisms, of a cam shaft adapted to be mounted in said crank case for operating said valve mechanisms, a supporting plate, rocker arms mounted thereon in pairs and adapted to be independently operated by said cam 115 shaft, and means for securing said supporting plate to said crank case, said supporting plate being adapted to be removed from said crank case without disturbing said cam shaft.

3. In an internal combustion engine, the combination with a crank case, of a plurality of cylinders mounted thereon in V relation and provided with reciprocating valve mechanisms, a cam shaft mounted in bearings in 130

- said crank case for operating said valve mechanisms, of a supporting plate, rocker arms mounted thereon in pairs and adapted to be independently operated by said cam shaft, and means for mounting said supporting plate on said crank case, said supporting plate being adapted to be removed from said crank case without disturbing the adjustment of said cam shaft bearings.
- 10 4. In an internal combustion engine, the combination with a crank case, of a plurality of cylinders mounted thereon in V relation and provided with reciprocating valve mechanisms, a cam shaft, and valve tappets mounted in said crank case, of a supporting plate, rocker arms mounted thereon in pairs and adapted to be independently operated by said cam shaft and to operate said tappets, said supporting plate being adapted to be secured to and removed from said crank case without disturbing the mounting of said valve tappets.
- 15 5. In an internal combustion engine, the combination with the crank case, a cam shaft mounted in bearings therein, and valve tappets also mounted in said crank case, of a supporting plate, rocker arms mounted thereon, and adapted to be operated by said cam shaft and to operate said tappets, and means for detachably securing said supporting plate to said crank case, said supporting plate being adapted to be removed from said crank case with its associated rocker arms without disturbing the mounting of said cam shaft or said valve tappets.
- 20 6. In an internal combustion engine, the combination with a crank case, a cam shaft, bearings therefor and means formed integral with said crank case for supporting the bearings for the cam shaft, said cam shaft being adapted to be mounted in said crank case by an endwise movement of said shaft, of a supporting plate, rocker arms mounted thereon adapted to be operated by said cam shaft, and means for detachably securing said supporting plate to said crank case, said supporting plate and said rocker arms being adapted to be removed from operative position without disturbing said cam shaft.
- 25 7. In an internal combustion engine, the combination of a crank case having an opening therein, a cam shaft adapted to be mounted in bearings in said crank case arranged adjacent said opening, means for securing said bearings and cam shaft in position in said crank case, of a cover plate for said opening, rocker arms mounted on said plate and adapted to be operated by said cam shaft, and means for detachably securing said plate to said crank case.
- 30 8. In an internal combustion engine, the combination with a crank case, a crank shaft and a cam shaft mounted therein in the same vertical plane, of a supporting plate, rocker arms mounted on said supporting
- plate and adapted to be operated by said cam shaft, and means for securing said supporting plate to said crank case.
9. In an internal combustion engine, the combination with a crank case, a crank shaft 70 mounted therein, and a cam shaft having its axis in the same vertical plane as the crank shaft, mounted in bearings in said crank case, of a supporting plate, rocker arms mounted thereon and adapted to be operated 75 by said cam shaft, and means for securing said supporting plate to said crank case, said supporting plate being adapted to be removed from said crank case without disturbing the mounting of said cam shaft in 80 said crank case.
10. In an internal combustion engine, the combination with a crank case, of a plurality of cylinders mounted thereon in V relation and provided with reciprocating 85 valve mechanisms, a crank shaft and a cam shaft mounted therein, and means for securing said shafts in driving relation, of a supporting plate having rocker arms mounted thereon in pairs, and adapted to 90 be independently operated by said cam shaft and to operate said valve mechanisms, said rocker arms and said supporting plate being adapted to be assembled in operative position and disassembled therefrom without disturbing the means for retaining said cam shaft and said crank shaft in driving relation.
11. In an internal combustion engine, the combination with a crank case, a plurality 100 of cylinder blocks mounted thereon in V relation, and valve mechanisms arranged in the adjacent faces of said blocks, of means for operating said valve mechanisms comprising a cam shaft between said blocks and 105 mounted in said crank case, a supporting plate detachably secured to said crank case, and a plurality of rocker arms mounted thereon between said shaft and said valve mechanisms.
12. In an internal combustion engine, the combination with a crank case, a plurality of cylinder blocks mounted thereon in V relation and valve mechanisms arranged in the adjacent faces of said blocks, of means 115 for operating said valve mechanisms comprising a cam shaft between said blocks and mounted in said crank case, a supporting plate, rocker arms mounted thereon, adapted to be operated by said cam shaft and to 120 operate said valve mechanism, said supporting plate being adapted to be secured to said crank case and to be removed therefrom without disturbing said cam shaft.
13. In an internal combustion engine, the 125 combination with a crank case, a plurality of cylinder blocks mounted thereon in V relation, and valve mechanisms comprising reciprocating valves arranged in the adjacent faces of said blocks, of means for oper- 130

ating said valve mechanisms comprising a cam shaft, said valves and cam shaft not having coincident axes, and means arranged between said valve and cam shaft having a substantially constant sliding contact with said valve mechanisms.

14. In an internal combustion engine, the combination with a crank case, a cylinder provided with a reciprocating valve mechanism, a cam shaft therefor, said valve mechanism and cam shaft not having coincident axes, and means interposed between said parts and having a substantially constant point contact with said valve mechanism, and means being mounted on a supporting plate detachably secured to said crank case.

15. In an internal combustion engine, the combination with a crank case, a plurality of cylinder blocks mounted thereon in V relation and provided with reciprocating valve mechanisms arranged in the adjacent faces of said blocks, of means for operating said valve mechanisms comprising a cam shaft, and means arranged between said shaft and said valve having a substantially constant sliding contact with said valve mechanisms.

16. In an internal combustion engine, the combination with a crank case, a plurality of cylinder blocks mounted thereon in V relation and provided with reciprocating valve mechanisms arranged in the adjacent faces of said blocks, of means for operating said valve mechanisms comprising a cam shaft, said valve mechanisms and cam shaft being so arranged that their axes do not

coincide, and rocker arms interposed therebetween having a substantially constant sliding contact with said valve mechanisms.

17. In an internal combustion engine, the combination with a crank case, a plurality of cylinder blocks mounted thereon in V relation and provided with reciprocating valve mechanisms arranged in the adjacent faces of said blocks, of means for operating said valve mechanisms comprising a cam shaft, said valve mechanisms and cam shaft being so arranged that their axes do not coincide, and rocker arms interposed therebetween, said valve mechanisms and rocker arms having their contacting portions so formed that a substantially constant point contact is provided therebetween.

18. In an internal combustion engine, the combination with a crank case, a plurality of cylinder blocks mounted thereon in V relation and provided with reciprocating valve mechanisms arranged in the adjacent faces of said blocks, of means for operating said valve mechanisms comprising a cam shaft, said valve mechanisms and cam shaft being so arranged that their axes do not coincide, and rocker arms interposed therebetween, said rocker arms having means provided for maintaining a substantially constant point contact between the cam shaft and valve mechanism respectively.

In testimony whereof I affix my signature in the presence of two witnesses.

D. McCALL WHITE.
